US00D977664S

(12) **United States Design Patent** (10) **Patent No.:** **US D977,664 S**
Wersland et al. (45) **Date of Patent:** **** Feb. 7, 2023**

- (54) **PERCUSSIVE MASSAGE DEVICE**
(71) Applicant: **Therabody, Inc.**, Los Angeles, CA (US)
(72) Inventors: **Jason Wersland**, Los Angeles, CA (US); **Benjamin Nazarian**, Los Angeles, CA (US); **Jaime Sanchez Solana**, Los Angeles, CA (US); **Eduardo Merino**, Los Angeles, CA (US); **Trent Hernandez**, Los Angeles, CA (US)
(73) Assignee: **Therabody, Inc.**, Los Angeles, CA (US)

(**) Term: **15 Years**

(21) Appl. No.: **29/828,354**

(22) Filed: **Feb. 25, 2022**

Related U.S. Application Data

- (60) Continuation of application No. 29/728,609, filed on Mar. 19, 2020, now Pat. No. Des. 949,391, which is a division of application No. 29/708,809, filed on Oct. 9, 2019, now Pat. No. Des. 884,915, which is a continuation-in-part of application No. 29/674,846, filed on Dec. 26, 2018, now Pat. No. Des. 880,716.

CLAIM

The ornamental design for a percussive massage device, as shown and described.

DESCRIPTION

FIG. 1 is a top perspective view of a percussive massage device, showing our new design;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof;
FIG. 7 is a bottom plan view thereof; and,
FIG. 8 is a bottom perspective view thereof.

The broken lines in the figures show portions of the percussive massage device that form no part of the claimed design.

1 Claim, 6 Drawing Sheets
